UNITED STATES PATENT OFFICE

155,155

DESIGN FOR A COMBINED BOWLING BALL
AND SHOE CARRIER

Myron L. Haney, Evanston, Ill.

Application August 1, 1947, Serial No. 140,650

Term of patent 3½ years

(Cl. D34—5)

To all whom it may concern:

Be it known that I, Myron L. Haney, a citizen of the United States, residing at Evanston, in the county of Cook and State of Illinois, have invented a new, original, and ornamental Design for Combined Bowling Ball and Shoe Carrier, of which the following is a specification, reference being had to the accompanying drawing, forming part thereof.

In the drawing,

Fig. 1 is a view in side elevation of the combined bowling ball and shoe carrier showing the new design thereof;

Fig. 2 is also a view in end elevation of the carrier of Fig. 1, the view being taken from a position 90° removed from that of Fig. 1;

Fig. 3 is a top plan view; and Fig. 4 is a bottom plan view of the carrier of Fig. 1.

I claim:

The ornamental design for a combined bowling ball and shoe carrier, substantially as shown.

MYRON L. HANEY.
